UNITED STATES PATENT OFFICE.

NORMAN J. URQUHART, OF NEW ORLEANS, LOUISIANA, ASSIGNOR OF ONE-TWENTIETH
TO LIONEL ADAMS, OF NEW ORLEANS, LOUISIANA.

CALCINATION KILN.

Application filed February 9, 1924. Serial No. 691,784.

This invention relates to a calcination kiln and process and it is an object of the invention to provide novel and improved means whereby the material to be treated, after being finely comminuted, has each of the finely comminuted particles brought into direct contact with a live flame, the zone of flame or heat being of desired length and the particles travelling through such zone to the collecting pot.

Furthermore, it is an object of the invention to provide novel and improved means whereby the heat zone increases in temperature toward the retort, the associated burners for creating the requisite flame being separately regulated so that any degree of temperature may be had at substantially any point along the zone or in other words the zone of regulation of heat is entirely under control at all times.

Furthermore, the invention has for an object to provide novel and improved means whereby the requisite calcination or chemical changes of the material occurs within the flume leading to the collecting pot.

The invention consists in the details of construction and in the combination and arrangement of the several parts of my improved calcination kiln and process whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in side elevation but of a diagrammatic character illustrating a kiln constructed in accordance with an embodiment of my invention;

Figure 2 is a view in top plan and also of a diagrammatic character of the flume as embodied in Figure 1;

Figure 3 is a fragmentary sectional view taken horizontally through the central portion of Figure 2;

Figure 4 is an enlarged sectional view taken transversely of the flume.

As disclosed in the accompanying drawings, R denotes a retort of a conventional type and discharging in the pot P thereof is

the flume F. The flume F is of desired length and disposed on an incline toward the pot so that the material to be treated may travel therethrough by gravity. Discharging within the upper or receiving end 60 portion of the flume F is a hopper H which contains the material or ore to be treated. This material or ore before being applied within the hopper is finely comminuted.

The upper or outer end of the flume F has 65 extending therein a burner 1 herein disclosed of a hydrocarbon or other type and which has associated therewith a steam or compressed air line 2 to assure requisite pressure, said pressure for the calcination of 70 lime-stone or the like being preferably about one-hundred and seventy-five pounds.

In communication with the flume at points spaced longitudinally thereof and at opposite sides thereof are the branches B and 75 extending in the outer end portion of each of said branches are the burners 3, each of which also having associated therewith a steam or compressed air line 4 to create the requisite pressure. Each of the burners 1 80 and 3 is under control of a valve 5 of any desired type whereby the requisite regulation can be had as will hereinafter be more particularly referred to.

The flume F and each of its branches B 85 may be formed as desired but preferably comprises a steel jacket 6 the top of which being readily removable so that access may be conveniently had to the lining 7 thereof, said lining preferably consisting of fire clay 90 bricks or other refractory materials. By this means, the flume may be readily cleaned out or repaired as the occasions of practice may necessitate.

The flames of the burners 1 and 3 project 95 within the flume F proper and are disposed downwardly of the flume or in a direction toward the collecting pot P, said flames providing a range of heat extending the entire length of the flume or between the points 100 x and y, the temperature within the flume increasing from the upper point x toward the lower point y. In practice, in the calcination of limestone or the like the heat preferably ranges from 600° F. to 6,000° 105 F., although it is to be understood that this may be readily regulated as the occasions of practice may necessitate and in accordance with the character of the material to be treated.

- In practice, the finely comminuted particles of raw material or ore, such as limestone or the like, is projected or dropped into the upper end of the flume from the hopper H and passes into the fire zone within the flume F, each particle coming in direct contact with the flame. In the present instance, the invention is particularly adapted for the production of lime and the flame is therefore of an oxidizing type. In the burning or calcination of the limestone or the like to produce hot lime or (CaO) the flame changes the calcium carbonate into a calcium oxide which travels by gravity through the living flame in the flume. The pressure generated by the flames from the burners 1 and 3 causes the material current to flow in the direction of the collecting pot carrying along the finely comminuted material which is being changed chemically as it passes down through the flume. In the calcination of limestone or the like, this travelling is preferably at the rate of four feet per second.
- If it is desirable to introduce a faster action, suitable pressure can be introduced into the finely comminuted material as it flows into the flume and increased pressure can also be introduced to the burners.
- The material as delivered to the collecting pot and particularly in the calcination of limestone or the like constitutes a finished product and can then be readily carried to the customary cooling chamber or the like and in practice, the entire production of the lime from the raw material and ready for packing can be accomplished within substantially a period of two hours.
- Should it be desirable to have perfect control of the amount of heat at any point

along the flume F it is possible to so regulate each burner separately and distinctly that any degree of temperature may be had at substantially any point. By this the zonal regulation of heat is entirely under 45 control at all times.

From the foregoing description it is thought to be obvious that a calcination kiln and process constructed in accordance with my invention is particularly well adapted 50 for use by reason of the convenience and facility with which it may be assembled and operated, and it will also be obvious that my invention is susceptible of some change and modification without departing 55 from the principles and spirit thereof and for this reason I do not wish to be understood as limiting myself to the precise arrangement and formation of the several parts herein shown in carrying out my invention in practice except as hereinafter claimed.

I claim:—

A kiln comprising, in combination, a collecting pot, a flume adapted to deliver to the collecting pot, said flume having branches in communication therewith at points spaced longitudinally thereof and at opposite sides of the flume, said branches extending diagonally with respect to the flume in the direction of the collecting pot, pressure feed fluid fuel burners arranged within said branches and directing their flames within the flume in a direction toward the collecting pot, and means for regulating the pressure for each burner.

In testimony whereof I hereunto affix my signature.

NORMAN J. URQUHART.
